FABRICATION OF HOLLOW ARTICLES

Theron F. Pauls, Godfrey, Ill., assignor to Olin Mathieson Chemical Corporation, East Alton, Ill., a corporation of Virginia

Filed Apr. 16, 1956, Ser. No. 578,296

6 Claims. (Cl. 113—44)

This invention relates to the fabrication of hollow articles and more specifically to the fabrication of hollow articles which are smooth on one side.

In the fabrication of hollow sheet metal panels by a well known process, two sheets of metal are arranged in stack-like fashion with a design of weld-inhibiting material applied to a portion of one of the adjacent faces of the sheets. The sheets are secured together to prevent relative slippage and are then welded together in their adjacent areas not separated by the weld-inhibiting material in any suitable manner such as by hot rolling. As the sheets are being welded together by hot rolling they are elongated in the direction of rolling and therefore the design of weld-inhibiting material must be foreshortened in the intended direction of rolling when it is applied to the sheet. After the sheets are welded together they are usually softened as by annealing and the unjoined portion to which the weld-inhibiting material has been applied is outwardly expanded as by injecting therein a fluid pressure of sufficient magnitude to permanently distend the sheets in the area adjacent to the weld-inhibiting design which may assume any desired configuration, for example, a design which will define, after expansion of the panel, a fluid conveying circuit of the type required in refrigerator heat exchanger panels. The aforementioned process is more fully described in U.S. Patent 2,690,002, issued September 28, 1954.

This invention comprehends clamping a blank having an unjoined inner portion sandwiched between opposite outer surfaces of the blank between a hard and a compressible pressure pad and then expanding the unjoined portion of the blank by injecting therein a fluid pressure. The blank is distended on the face adjacent the compressible pressure pad and is smooth on the side adjacent the hard pad.

As used herein, the term "smooth" means a surface substantially devoid of depressions or protrusions in the overall general configuration of the surface.

This invention is directed primarily to the fabrication of metal panels, but in part the invention is equally applicable to panels fabricated from materials other than metal, such as various plastics, and to panels fabricated from dissimilar materials such as metal and a plastic joined together with an unjoined portion between the sheets.

It is an object of this invention to fabricate a hollow panel in which one side is smooth and the other side is distended.

Another object of this invention is to fabricate a panel having formed therein a hollow portion, such as fluid carrying conduits, the panel having a smooth surface and an opposite surface having protrusions conforming to the distentions of the hollow portion.

Another object of this invention is to provide an improved method of fabricating panels of the type disclosed in the aforementioned patent, U.S. 2,690,002, in which one of the outer surfaces has a high degree of smoothness.

Additional objects and advantages will be apparent from the following description and drawings in which:

FIGURES 1 and 2 indicate schematically a process for fabricating a blank from which a hollow smooth-sided panel is subsequently formed, and more specifically:

FIGURE 1 is a perspective view of a sheet of material

2

having applied to the surface thereof a pattern of weld-inhibiting material;

FIGURE 2 is a perspective view of the sheet shown in FIGURE 1 with a second sheet superimposed thereon in laminar fashion and tacked thereto as by spot welding, with the pattern of weld-inhibiting material sandwiched between the sheets and showing the sheets being welded together in a rolling mill to form a blank;

FIGURE 3 is a sectional schematic view of the resultant blank of FIGURE 2 with the line 3—3 in FIGURE 1 indicating the portion of the weld-inhibiting pattern shown in FIGURE 3, and showing the blank positioned between an embodiment of a pair of pressure pads;

FIGURE 4 is a sectional schematic view of the resultant blank of FIGURE 2 positioned between another embodiment of pressure pads, and with the same section through the blank as in FIGURE 3;

FIGURE 5 is a sectional schematic view similar to FIGURE 3 after the pressure pads have been clamped against the blank and the unjoined portion of the blank expanded;

FIGURE 6 is a schematic view of a control system for actuating the pressure pads and for expanding the blank;

FIGURE 7 is a perspective view of the expanded blank of FIGURE 5;

FIGURE 8 is a perspective view of the opposite side of the blank shown in FIGURE 7.

Referring to the drawings, a sheet 1 such as aluminum or copper has applied to a clean surface 3 thereof a serpentine design 5 and an inlet 6 of weld-inhibiting material. A second sheet 7 is superimposed on the surface 3 of the first sheet 1. The two sheets are then tacked together as by spot welding 9 to prevent relative slippage

35 of the adjacent surfaces of the sheets during a subsequent welding operation. After the sheets have been tacked together they are welded together along their adjacent surfaces not separated by the weld-inhibiting material 5. One well known method of welding the sheets together is by hot rolling, in which the sheets are first heated and then passed through mill rolls 11 between which they are reduced in thickness and elongated in the direction of rolling. If desired, the resultant blank 13 having an unjoined inner portion 15 may be softened in any appropriate manner as by annealing and thereafter the blank may be cold rolled to provide a more even thickness and again annealed. The inlet design of weld-inhibiting material produces an unjoined inlet into the unjoined serpentine design after welding together of the sheets.

Referring to FIGURE 3, the resultant blank is positioned between a compressible pressure pad 17 and a hard pressure pad 19. The compressible pressure pad is mounted on a hard backing plate 21 having confining side walls 23 which engage the side wall of the compressible pad limiting outward displacement of the pad. The compressible pressure pad 17 and its backing plate 21 are positioned on a fixed jaw 25 of the press 27 and the hard pressure pad 19 is secured to a vertically moving jaw 29 of the press. The movable upper jaw 29 of the press is secured to a plunger 31 received in a cylinder 33 with a fluid-tight sliding fit. The movable jaw 29 is maintained in a raised position by a spring 35 engaging a shoulder 37 on the lower end of the cylinder 33 and a shoulder 39 on the plunger 31. The cylinder 33 is fixed with respect to the lower jaw 25 of the press in any appropriate manner as by arms 41. A fluid pressure conveying conduit 43 opens into the upper end of the cylinder 33 for injecting a fluid into the cylinder 33 thereby forcing the plunger 31 downward and the hard pressure pad 19 against the compressible pressure pad 17.

The blank 13 is inserted between the pressure pads and a fluid pressure conveying nozzle 45 is inserted into the inlet in the blank. A fluid pressure is conveyed through the conduit 43 into the cylinder 33 clamping the hard upper pressure pad 19 against the lower compressible pressure pad 17 and the horizontal surfaces of the walls 23 of its backing plate 21. The blank 13 is sandwiched between the hard pressure pad and the compressible pressure pad. The unjoined portion of the blank 13 is then expanded by injecting a fluid pressure therein through the nozzle 45 and conduit 46 connected thereto.

In order to assure a smooth-sided hollow article 47 devoid of protrusions, the total compression of a compressible rubber pad 17 should be limited to between twenty and thirty percent for a 30 Shore-durometer rubber. If the percent of compression of the rubber is increased past this limit, the intended smooth side will tend to have formed therein distentions. The percentage of compression is controlled by the height of the side walls 23 relative to the thickness of the rubber pad 17. Preferably the compressible pad should also be resilient such as a rubber pad, however, a pad which is not resilient will function properly to a degree but may not be reused.

FIGURE 4 shows another embodiment of the invention. In this embodiment, a hard pressure pad 49 is positioned on a lower fixed jaw 51 of a press 53 and a hydraulic chamber 55 having a resilient diaphragm 57 adjacent the hard pressure pad 49 replaces the compressible pressure pad 17 in the embodiment shown in FIGURE 3. The resilient diaphragm 57 is secured to the inner surface 59 of a peripheral side wall 60 of a chambered member 61 secured to an upper vertical movable jaw 63 of the press 53. A fluid pressure supply conduit 70 opens into the hydraulic chamber 55 for introducing therein a fluid. The movable upper jaw 63 of the press is secured to a screw 67 rotatably mounted as at 69, on the upper surface of the movable jaw. The screw 67 is threaded into a threaded socket 71 rigidly fixed to the lower jaw 51 of the press in any suitable manner such as by arms 73. Thus, by rotating the screw 67 the upper movable jaw 63 of the press may be raised or lowered. The blank 13 is inserted between the hard pressure pad 49 and the diaphragm 57 and the nozzle 45 is inserted into the inlet in the blank. The screw 67 is then rotated to clamp the side walls 60 of the hydraulic chamber against the hard pressure pad 49. Fluid pressure is injected through a conduit 70 into the hydraulic chamber 55 and the blank 13 is then expanded by injecting a fluid pressure into the unjoined portion thereof, through the nozzle 45 and a conduit 46 connected to the nozzle.

The outward distention 77 of the unjoined portion 15 of the blank 13 is controlled by the difference between the force exerted within the unjoined portion of the blank and the force exerted by the compressible pressure pad 17 or the diaphragm 57 against the outer surface of the blank. In the embodiment shown in FIGURE 3, this control is obtained by increasing or decreasing the thickness of the compressible pad 17 relative to the height of the backing plate side walls 23, since the hard pressure pad 19 engages the side walls. In the embodiment shown in FIGURE 4, the force exerted against the outer face of the blank 13 is controlled solely by the hydraulic pressure exerted by the fluid in the chamber 55 against the diaphragm 57.

Referring to FIGURE 6, with the press 53 shown in FIGURE 4 closed and the blank 13 sandwiched between the hard pressure pad 49 and the diaphragm 57 and with all the valves closed, valves A and C are opened and a pressure of about 1,000 pounds per square inch is introduced from a pump into the hydraulic chamber 55 through conduit 70. Valve C is then closed and valve B is opened, injecting a pressure of about 1,000 pounds into the unjoined portion 15 of the blank and the pressure is then raised to between 1,500 and 2,000 pounds per

square inch, depending on the thickness of the blank and the pressure required to fully distend the particular pattern of the unjoined portion of the blank. Valve A is then closed and valve C is opened, equalizing the force exerted within the unjoined portion of the blank and on the opposite exterior faces of the panel 47. Valve D is then opened, simultaneously discharging the pressure within the distended portion 75 of the hollow article 47 and within the hydraulic chamber 55. The pressures indicated above are intended merely to clarify the example, the pressure actually used will depend on the strength and thickness of the panel and the unjoined pattern design.

It is usually necessary for these pressures to be released simultaneously. If the pressure within the unjoined portion 75 of the panel 47 is released first the pressure of the diaphragm 57 against the distended portion of the panel may cause the distention to collapse. Conversely, if the pressure within the hydraulic chamber 55 is released first the pressure within the distended portion 75 of the panel 47 will cause the panel to rupture. After the pressures have been released, the screw 67 is rotated to separate the hard and compressible pressure pads and the resultant hollow article 47 is removed from the press 53.

As shown in FIGURES 7 and 8, the hollow article 47 is distended on one side 77 and smooth on the opposite side 79 which was against the hard pressure pad 19 or 49.

Referring to FIGURE 3, the process of expanding the blank is substantially the same as the method of FIGURE 4 with the following exceptions: With all the valves shown in FIGURE 6 closed, valves C and A are opened forcing the hard pressure pad 19 against the side walls 23 of the backing plate 21 of the compressible pressure pad 17. It is only necessary that sufficient pressure be applied through valve C to firmly press the hard pad 19 against the side walls 23. Valve B is then opened, exerting the same pressure within the unjoined portion 15 of the blank 13 as is exerted in the hydraulic chamber 33 and valve C is closed. The pressure from the pump is then increased sufficiently to fully inflate the unjoined portion of the blank. The pressure required will vary depending on the thickness and strength of the blank and the configuration of the unjoined portion thereof. Valve A is then closed, and valve D and valve C are opened concurrently, simultaneously releasing the pressure in the hydraulic chamber 33 and within the distended portion of the panel. If the unjoined portion of the blank is distended to too great an extent, the smooth side of the panel may tend to pull in. This effect may be eliminated by reducing the expansion pressure exerted within the unjoined portion of the blank.

Although the invention has been described with reference to certain specific embodiments, materials and details, various modifications and changes will be apparent to one skilled in the art and the invention is therefore not to be limited to such embodiments, materials or details except as set forth in the appended claims.

I claim:

1. An apparatus for use in expanding a hollow article from a blank formed of a plurality of sheets with said blank having an unjoined interior portion defined within joined portions of said sheets and also provided with an inlet for fluid pressure to said unjoined portion with said unjoined portion being adapted to contain a fluid under pressure, said apparatus comprising a rigid pad having a surface against which one side of said blank is placed in adjacent relationship, compressible clamping pressure means adjacent the other side of said blank for applying a uniform pressure on the other side of said blank with said compressible clamping pressure means being operatively connected to said pad and opposite said surface so that said compressible clamping pressure means holds said blank against said surface, engaging means operatively connected to said compressible clamping pressure means

for engaging said compressible clamping pressure means with and against said other side of said blank so that said compressible clamping pressure means holds said one side of said blank substantially contiguously against said surface during expansion of each unjoined portion, fluid injecting means adapted to be operatively connected to said inlet while said blank is held against said surface by said compressible clamping pressure means for injecting into said unjoined portion a fluid under pressure of sufficient magnitude to expand said unjoined portion while said one side is held against said surface, and pressure relieving means operatively connected to said compressible clamping pressure means and said fluid injecting means to concurrently relieve the forces of said compressible clamping pressure means and the pressure applied within the said unjoined portion of said blank.

2. The apparatus of claim 1 wherein said compressible clamping pressure means is a resilient solid.

3. The apparatus of claim 2 wherein said resilient solid is rubber.

4. The apparatus of claim 1 wherein said compressible clamping pressure means comprises a hydraulic chamber.

5. The apparatus of claim 4 wherein said hydraulic chamber has a flexible diaphragm adjacent said blank.

6. An apparatus for expanding a blank formed of a plurality of sheets having an unjoined interior portion defined and contained within joined portions of said sheets provided with an inlet for fluid pressure to said unjoined portion with said unjoined portion being adapted to contain a fluid under pressure, said apparatus comprising a pair of opposed pressure means operatively connected to each other for receiving said blank therebetween, one of said pressure means being rigid and non-compressible and the other of said pressure means being compressible, said rigid means having a surface against which one side of said blank is placed in adjacent relationship, engaging means operatively connected to said compressible pressure means for engaging said com-

5
10
15

pressible pressure means with the other side of said blank so that said compressible pressure means applies a uniform pressure to said other side to hold said one side of said blank substantially contiguously against said surface during expansion of said unjoined portion, fluid injecting means adapted to be operatively connected to said inlet while said blank is held against said surface by said compressible pressure means for injecting into said unjoined portion for expansion thereof a fluid under pressure of sufficient magnitude to impress said other side of said blank opposite said unjoined portion into said compressible means, and pressure releasing means operatively connected to said compressible pressure means and to said fluid injecting means to simultaneously relieve the force of said compressible pressure means and said fluid pressure applied within the unjoined interior portion of said blank.
